[57] CLAIM

The ornamental design for a food container or the like, substantially as is shown and described.

DESCRIPTION

FIG. 1 is a top, front left side perspective view of a food container or the like showing my new design, shown in a disassembled view for clarity of illustration;

FIG. 2 is a top plan view thereof;

FIG. 3 is a left side elevation thereof;

FIG. 4 is a bottom plan view thereof;

FIG. 5 is a front elevation of the tray portion shown separately for clarity of illustration;

FIG. 6 is a rear elevation of the tray portion shown separately for clarity of illustration;

FIG. 7 is a rear elevation thereof; and

FIG. 8 is a top, front, left side perspective view thereof shown in an assembled view.
